UNITED STATES PATENT OFFICE.

WILLIAM THOMAS BUCKINGHAM ROBERTS AND FRED RICKS, OF LEICESTER, ENGLAND, ASSIGNEES TO UNITED SHOE MACHINERY CORPORATION, OF PATERSON, NEW JERSEY, A CORPORATION OF NEW JERSEY.

STAMPING MECHANISM FOR EVENING AND GRADING MACHINES.

Application filed May 14, 1924. Serial No. 713,227.

To all whom it may concern:

Be it known that we, WILLIAM THOMAS BUCKINGHAM ROBERTS and FRED RICKS, subjects of the King of England, residing at 5 Leicester, Leicestershire, England, have invented certain Improvements in Stamping Mechanism for Evening and Grading Machines, of which the following description, in connection with the accompanying drawings, is a specification, like reference characters on the drawings indicating like parts in the several figures.

This invention relates to stamping mechanism and is herein illustrated as embodied 15 in a machine for stamping soles or similar blanks with sunken numerals to indicate the respective thicknesses of the thinnest spots of said soles or other blanks.

A machine of this general type is shown 20 and described in Patent No. 841,809, granted January 22, 1907, upon an application filed in the name of Nichols. In that machine there is provided a stamping wheel having numerals on its periphery and capable of 25 being adjusted about its axis to bring the desired numeral into operative position. The blank first passes between feeler rolls one of which rises and falls in response to thicker or thinner spots encountered in the 30 blank; and this rising and falling roll is so connected with the stamping wheel that said wheel is adjusted into a position to cause that numeral on its periphery, which represents in a selected unit of measurement 35 the thickness of the thinnest spot in the blank, to be brought into lowermost, operative position. The blank, after having passed from between the feeler rolls, is carried beneath the stamping wheel and at which 40 time a cam is rotated by which the wheel is normally held in raised position against the urge of a spring-actuated driver. Rotation of the cam causes the stamping wheel to be brought down forcibly upon the work 45 by the driver and then to be raised again into position to be adjusted by the passage of a succeeding blank through the feeler rolls. Blanks are thus fed one by one through the machine and stamped while 50 moving.

In machines of this type, certain undesirable results sometimes occur. The numeral impressed upon the blank may be blurred owing to too long a contact of the numeral

on the stamping wheel with the blank or 55 owing to double stamping due to an uncontrolled rebound or chattering of the stamping wheel. And this uncontrolled rebound may break certain parts of the machine, for example the cam which releases the wheel 60 for its downward stroke and then raises it. Again the depth of the numerals stamped upon the blanks, and consequently the distinctness of the numerals may vary with 65 blanks of different thicknesses by reason of the fact that the spring-actuated driver exerts its force during the entire stroke of 70 the stamping member so that a blow of considerably more force is struck upon a thin blank than upon a thick one.

The general object of the present invention is to obviate these and other disadvantages.

According to one feature of the present invention, the application of force to the 75 stamping member to drive it toward the work terminates before the stamping member reaches the work. In the illustrative machine the movement of the driver, by which the force is applied to the stamping 80 member, is arrested before the stamping member contacts with the work, the stamping member completing its movement alone under the impulse imparted to it by the driver. This impulse being always the same, 85 the force with which the stamping member strikes the work is thus substantially uniform irrespective of variations in the thickness of the work—or at least substantially uniform within the limits of variation in 90 thickness encountered in sole blanks and similar articles. *

In machines of this kind, as has been explained above, the stamping member frequently rebounds from the work and comes 95 down a second time before it is raised by the cam. In order to obviate the tendency to blur the numeral stamped upon the moving blank when there is such a second descent, means are provided, in accordance with 100 another feature of the invention, for raising the stamping member quickly from the work and holding it raised. In the illustrative machine, a spring is located between the 105 carrier of the stamping member and the frame of the machine in position to be compressed during the stamping stroke of the carrier. This spring not only prevents the

double stamping referred to above, but ensures that the stamping member shall not dwell upon the moving work and also obviates the tendency which formerly existed 5 to the breaking of the lifting cam by the uncontrolled rebound or chattering of the carrier of the stamping member.

These and other features of the invention including certain details of construction and 10 combinations of parts will be described as embodied in an illustrative machine and pointed out in the appended claims.

Figure 1 of the drawings is a front view partly in elevation and partly in section of 15 a portion of a machine in which the present invention is embodied, and

Figure 2 is an elevation of part of the construction shown in Figure 1 viewed from the left.

20 Only the stamping mechanism and a portion of the bed of the machine over which the blanks are fed have been shown since otherwise the machine is or may be substantially the same as the machine of Patent 25 No. 1,182,105, granted May 9, 1916, upon an application filed in the name of Roberts. It will be understood that each blank first passes through a feeler mechanism which operates to turn the stamping 30 wheel into a position such that when the stamping wheel is later brought down upon the blank it will indent the blank with the proper numeral to indicate the thickness of the thinnest spot in a selected area or locality of the blank encountered by the feeler mechanism. This feeler mechanism is located in front of the stamping wheel 1, as viewed in Figure 1; and the blank, after it leaves said mechanism, is fed beneath the 35 stamping wheel to a splitting or evenning mechanism located behind the stamping wheel. The stamping wheel is normally held in raised position above the bed 3 against the force of a spring-actuated driver 5 by a cam 7 carried at the outer end of a rotary shaft 9, the spring which urges the driver downwardly at all times about the pivot 12 being indicated at 10. While the blank is passing beneath the stamping 40 wheel 1, a clutch is automatically thrown in to impart one revolution to the shaft 9 and cam 7 with the result that the stamping wheel is forcibly brought down upon the blank by the action of the spring driver 5 and is then raised once more by the cam into the position shown. As thus far described, the mechanism is or may be the same as in the machine of Patent No. 1,182,105, referred to above.

45 The stamping wheel 1 is mounted in a carrier 14 which is slidable in vertical guideways in the frame of the machine. At its upper end is a cup-shaped member 13 which receives the lower, rounded end of a rod 15, the upper end of said rod being

received in a similar cup-shaped member 16 carried at the outer end of the spring-actuated driver 5. Formed on the under side of the driver 5 is a hardened face 17 which, when the driver swings downwardly, contacts with an adjustable stop 19. The driver is thus arrested in its downward movement before the stamping wheel reaches the blank, but the carrier 14 continues its downward movement under the 70 impetus given to it by the driver. Downward movement of the carrier compresses a spring 21 which is considerably weaker than the spring 10 but is strong enough to raise the carrier. The carrier, however, 75 usually rebounds, and the principal function of the weaker spring is to prevent the carrier from immediately descending a second time whereby a blurred mark would result upon the blank. The spring 21 at 80 its lower end rests upon the bottom of a socket formed in the frame of the machine, and at its upper end engages the under side of a bracket 23 which is fastened to the carrier 14. A pin 25 carried by the bracket 90 extends into the coils of the spring and serves to prevent the spring from being displaced. The stop 19 is vertically adjustable by reason of the fact that its stem is threaded into a socket formed in the 95 frame of the machine. A check nut 27 holds it in adjusted position.

Referring now more particularly to Figure 2, the direction of rotation of the cam 7 is indicated by the arrow. Normally the 100 trailing end 29 engages the under face of a hardened block 31 which is fastened to the carrier 14 and thus holds the carrier, and with it the stamping wheel, in raised position. When, in the course of the 105 operation of the machine, a blank passes beneath the stamping wheel and one revolution is imparted to the cam, the trailing end 29 of the cam passes out from beneath the block 31 whereupon the driver 5 instantly causes the carrier 14, and with it the stamping wheel, to be moved forcibly downward to mark the blank. The carrier then instantly rises, either by reason of 110 its rebound or by reason of the action of the spring 21 or by reason of both; and thereafter, during the completion of the 115 rotation of the cam 7, the lifting end 33 thereof contacts with the under face of the hardened block 31 and raises the carrier and stamping wheel against the force of the spring 10, the parts coming to rest in the positions shown with the trailing end of the cam engaging the block 31.

The driver 5 thus has a fixed range of 120 movement, such movement being arrested before the stamping wheel contacts with the work. As soon as the driver contacts with the stop 19 the application of force 125 to the stamping wheel terminates, the re- 130

maining downward movement of the stamping wheel being due to the impulse imparted to it by the driver. After the stamping wheel has struck and marked the blank, 5 it may rebound, being assisted in this rebound by the action of the spring 21 which was compressed by the downward movement of the stamping wheel carrier.

With this construction the force with 10 which the stamping wheel strikes the work is substantially the same irrespective of variations in the thickness of the blanks, and there is no double stamping due to a second descent of the stamping wheel after 15 it has rebounded. The numerals impressed upon the blanks are thus substantially uniform as to depth and free from blurring.

Having thus described our invention, what we claim as new and desire to secure by 20 Letters Patent of the United States is:—

1. In a machine of the class described, a stamping member, a driver therefor, a spring adapted to urge the driver in a direction to impart stamping movement to the stamping 25 member, means for normally holding the stamping member in raised position against the force of the driver spring, said means being adapted to be moved to release the stamping member and thereby permit the 30 driver to impart a stamping stroke to the stamping member, and a stop for arresting the movement of the driver before the stamping member completes its stroke.

2. In a machine in which a blank is moved 35 past stamping mechanism and stamped while moving, a stamping member, a carrier therefor, a driver, a rigid member having one portion in contact with the driver and another portion in contact with the carrier, 40 a comparatively heavy spring urging the driver in a direction to actuate the carrier, means for raising the carrier against the force of the spring and for thereafter releasing the carrier to permit the driver to 45 operate, a stop to limit the extent of movement of the driver which follows release of the carrier, and a lighter spring for raising the carrier immediately after the stamping operation has been completed.

50 3. In a machine of the class described, a stamping member, a driver therefor, a spring adapted to urge the driver in a direction to impart stamping movement to the stamping member, means for normally holding the 55 stamping member in raised position against the force of the driver spring, said means being adapted to be moved to release the stamping member and thereby permit the driver to impart a stamping stroke to the stamping member, and a stop for arresting the movement of the driver before the

stampin member completes its stroke, said stop being adjustable to vary the extent of the path of movement of the driver.

4. In a machine of the class described, a stamping member, a spring for urging the stamping member toward the work, means for raising the stamping member and thereby putting the spring under tension and for normally holding the stamping member in raised position, means for tripping the stamping member whereby driving force is applied to said member by the spring, and means for terminating the application of the driving force before the stamping member reaches the work.

5. In a machine in which a blank is moved past stamping mechanism and stamped while moving, a stamping member, a driver therefor, a spring normally exerting force upon the driver in a direction to cause the stamping member to move toward the path of movement of the blank, means normally holding the stamping member spaced from said path against the force of the spring, means for operating the holding means to release the stamping member, and a stop for arresting the movement of the driver while the stamping member is still moving.

6. In a machine in which a blank is moved past stamping mechanism and stamped while moving, a bed over which the blank is fed, a stamping member, means for normally holding said member in raised position above the bed, a driver having a separable connection with the stamping member, a spring urging the driver and with it the stamping member downwardly, means for moving the holding means to release the stamping member, and a stop for arresting downward movement of the driver before the stamping member contacts with the work.

7. In a machine in which a blank is moved past stamping mechanism and stamped while moving, a bed over which the blank is fed, a stamping member, means for normally holding said member in raised position above the bed, a driver having a separable connection with the stamping member, a spring urging the driver and with it the stamping member downwardly, means for moving the holding means to release the stamping member, and a stop for arresting downward movement of the driver before the stamping member contacts with the work, said stop being adjustable to vary the locality at which the movement of the driver is arrested.

In testimony whereof we have signed our names to this specification.

WILLIAM THOMAS BUCKINGHAM ROBERTS.

FRED RICKS.
